UNITED STATES PATENT OFFICE.

RUPERT E. RUNDELL, OF ROCKVILLE CENTER, NEW YORK, ASSIGNOR TO INTERNATIONAL CIGAR MACHINERY COMPANY, A CORPORATION OF NEW JERSEY.

CIGAR-BUNCH-REDUCING MECHANISM.

Application filed December 22, 1923. Serial No. 682,172.

To all whom it may concern:

Be it known that I, RUPERT E. RUNDELL, a citizen of the United States, residing at Rockville Center, county of Nassau, and State of New York, have invented a new and useful Improvement in Cigar-Bunch-Reducing Mechanism, of which the following is a specification.

This invention relates to a cigar bunch reducing mechanism.

In making a fresh bunch cigar having one or more tapered ends, the bunch is first made with its mid-section of the proper size, and then its ends only are reduced to the desired size and form by compression shaping dies. In making a concentrated cigar, the bunch is first made slightly oversized throughout, and is then slightly reduced to gather the filler toward the axis of the bunch but without compression. The main object of the present invention is the production of a device which can be used for shaping the ends of a fresh bunch, or for gathering in toward its axis the filler of a concentrated bunch. A further object of the invention is the production of a device of this character which is simpler and more efficient than the devices heretofore known and used in bunch shaping. With these and other objects not specifically mentioned in view, the invention consists in certain constructions and combinations which will be hereinafter fully described and then specifically set forth in the claims hereunto appended.

In the accompanying drawings, which form a part of this specification and in which like characters of reference indicate the same or like parts, Fig. 1 is an end elevation, partly in section, of a device constructed in accordance with the invention; Figs. 2 and 3 are similar views illustrating the parts in different relation; Fig. 4 is a side elevation of the structure shown in Figs. 1 and 3, illustrating the parts in the position in which they are shown in Fig. 3; Fig. 5 is a perspective view diagrammatically illustrating complementary reducing devices for acting on a concentrated bunch; and Fig. 6 is a perspective view diagrammatically illustrating bunch reducing devices for acting on a fresh bunch to shape its ends only, the reducing devices shown in Figs. 5 and 6 being interchangeably mounted in the device shown in Figs. 1 to 4 inclusive.

In carrying the invention into effect, there is provided a series of three complementary reducing devices for acting on a bunch, and means for operating said devices in non-synchronism. In the best construction, said means includes a single cam actuated lever and operative connections, and the reducing devices may be either devices for shaping the ends of a fresh bunch by compression, or devices for ingathering the whole of a concentrated bunch without compression. The parts may be widely varied in construction within the scope of the claims, for the particular device selected to illustrate the invention is but one of many possible concrete embodiments of the same. The invention therefore is not to be restricted to the precise details of the structure shown and described.

Referring to the drawings, 7 is a bracket supporting the various parts of the device and is adapted to be supported on the bed of a cigar machine in connection with which the device is used.

For the purpose of acting upon the bunch to reduce the same, there are provided three complementary reducing devices 8, 9 and 10, all of which are movable in and out of position where they coact to perform the duty common to all. These reducing devices may be of the type illustrated in Fig. 5 when concentrated bunches are to be acted upon, or may be of the type illustrated in Fig. 6 when fresh bunches are to be acted upon, the devices being interchangeable. In either case, the reducing devices 8 and 9 will be removably secured to the upper ends of levers 11 and 12, by means of bolts 13. The levers 11 and 12 are respectively fulcrumed on shafts 14 and 15 journaled in suitable bearings in the bracket 7. The lower ends of the levers 11 and 12 are respectively connected with toggle links 16-17 which are also connected with a collar 18 loosely mounted on a sleeve 19 having a head 20 and a foot 21, the latter having a pin and slot connection with a cam actuated lever 22, the motion of which is controlled by a cam on the cigar machine in connection with which the device is used. Interposed between the collar 18 and the foot 21 is a spring 23 which normally acts to hold the collar 18 in the position shown in Figs. 1 and 2. The sleeve 19 surrounds a plunger 24 having at its lower end a collar

25, at its mid-section a collar 26, and at its upper end a thread 27, by means of which the reducing device 10 is removably secured to the plunger 24 in order that it may have 5 the same motion as said plunger.

By an inspection of Figs. 1 and 3, it will be readily understood that the reducing devices 8 and 9 are swingable about parallel axes, while the reducing device 10 is 10 reciprocable between said axes.

The device selected to illustrate the invention is further provided with a trimming mechanism of a well known type which includes trimming knives 28 mounted 15 on arms 29 fast on the shaft 15 before referred to. The shaft 15 also carries an arm 30 by means of which it is rocked at the proper time. This arm 30 is connected to one end of a link 31, the other end of the 20 link being connected to a cam actuated lever 32.

In the operation of the device, a bunch is brought to and placed upon the reducing member 10 by bunch carrying clips 33 deriving their motion from another part of the cigar machine in connection with which the present device is used. As soon as a bunch is placed upon the reducing device 10, the cam actuated lever 22 swings upwardly. 25 The spring 23 is so stiff that the upward movement of the end of the cam actuated lever 22 causes a like upward movement of the collar 18. During the first part of this movement, the toggle mechanism is operated and the bunch reducing devices 8 and 9 are swung from the position shown in Fig. 1 to the position shown in Fig. 2. Then, 30 the devices 8 and 9 having been brought together, the collar 18 is stopped by its contact with an abutment 34 on the bracket 7. At this time the head 20 of the sleeve 19 comes in contact with the collar 26 on the plunger 24. A further upward movement of the cam actuated lever 22 therefore 35 results in elevating the reducing device 10 from the position shown in Fig. 2 to the position shown in Fig. 3, the spring 23 being compressed during this movement. When the reducing devices reach the 40 position shown in Fig. 3, they are in position to perform their duty whether it be bunch end shaping or entire bunch concentrating. The cam actuated lever 32 then comes into 45 action to cause the knives 28 to trim off the ends of the bunch protruding from the reducing devices. All parts then return to 50 their initial position, as shown in Fig. 1; whereupon, the bunch may be removed from the mechanism and another inserted.

55 60 What is claimed is:

1. Cigar bunch reducing mechanism com-

prising three complemental reducing devices for acting on a bunch, and means for operating said devices in non-synchronism.

65

2. Cigar bunch reducing mechanism comprising three complemental reducing devices for acting on a bunch, and means for operating said devices in non-synchronism, said devices including interchangeable bunch concentrating forms or bunch shaping forms.

70

3. Cigar bunch reducing mechanism comprising three complemental reducing devices for acting on a bunch, and means for operating said devices in non-synchronism, two of said devices being swingable about parallel axes.

75

4. Cigar bunch reducing mechanism comprising three complemental reducing devices for acting on a bunch, and means for operating said devices in non-synchronism, one of said devices being reciprocable.

80

5. Cigar bunch reducing mechanism comprising three complemental reducing devices for acting on a bunch, and means for operation in non-synchronism, two of said devices being swingable about parallel axes and the other being reciprocable between said axes.

85

6. Cigar bunch reducing mechanism comprising three complemental reducing devices for acting on a bunch, and means for operating said devices in non-synchronism, said means including a single cam-actuated lever and operative connections.

90

7. Cigar bunch reducing mechanism comprising three complemental reducing devices for acting on a bunch, and means for operating said devices in non-synchronism, said means including a toggle mechanism simultaneously actuating two of said devices.

95

8. Cigar bunch reducing mechanism comprising three complemental reducing devices for acting on a bunch, and means for operating said devices in non-synchronism, said means including a cam-actuated plunger first actuating two of said devices and then the other.

100

9. Cigar bunch reducing mechanism comprising three complemental reducing devices for acting on a bunch, and means for operating said devices in non-synchronism, said means including a cam-actuated plunger, a spring operated by said plunger, a toggle mechanism operated by said spring and operating two of said devices, the other device being subsequently operated directly by said plunger.

105

In testimony whereof, I have signed my name to this specification.

RUPERT E. RUNDELL.
